COAL BUCKET PLOW

Filed Jan. 12, 1925

Fig. 1.

Fig. 2.

Inventor,
Norman H. McClevey,
By Joseph A. Minturn
Attorney.

UNITED STATES PATENT OFFICE.

NORMAN H. McCLEVEY, OF PETERSBURG, INDIANA.

COAL-BUCKET PLOW.

Application filed January 12, 1925. Serial No. 2,017.

To all whom it may concern:

Be it known that I, NORMAN H. McCLEVEY, a citizen of the United States, residing at Petersburg, in the county of Pike and State 5 of Indiana, have invented a new and useful Improvement in Coal-Bucket Plows, of which the following is a specification.

This invention is an improvement on the bucket for loading coal shown and described 10 in my application for patent filed July 14, 1924, Serial No. 725,852, wherein the inclined plate on the back of the bucket had a tendency when the empty bucket was travelling back for a new load to ride upon 15 and crush any lump coal in the path of the bucket resulting from spillage in the forward travel of the loaded bucket and there was no means provided for returning the spillage to the down coal to be gathered.

20 The object of this invention is to substitute an attachment to the bucket, in place of the inclined plate, which will put the spillage from the previous trip of the loaded bucket, back in the down coal to be gathered 25 thereby keeping the mine clean and avoiding the crushing of the spilled lump coal into fine coal of materially less commercial value.

I accomplish the above, and other minor 30 objects which will hereinafter appear, by the mechanism illustrated in the accompanying drawing, in which—

Fig. 1 is a view in side elevation of my improved coal bucket with the former inclined plate on the back end of the bucket 35 removed and a plow-like attachment substituted therefor, and Fig. 2, is a top plan view of the same.

The bucket comprises two parallel and 40 vertical sheet metal sides 3, 3, which are rigidly held in their spaced relation to each other by a solid sheet metal rear end 4, and by a channel bar 5 in front, extending transversely of the bucket. The front end of the bucket, below the channel bar 5, is substantially open for the entrance of loose down-coal when the bucket is drawn against it, and the bottom of the bucket is likewise 45 open for the discharge by gravity of the coal in the bucket when the latter is drawn upon 50 a platform having a suitable opening.

Runner plates 6, having forwardly and 55 upwardly sloping lower edges are attached to the sides 3, 3 to cause the bucket to ride over fixed lumps of coal and to keep the bucket from digging into the floor of the

mine on the forward travel of the loaded bucket.

A horizontal plate 7, is attached to the channel bar 5 and has a series of holes for the attachment of a cable by which the bucket is drawn forward; and a similar plate 8, also having a series of holes for the attachment of a cable by which the bucket is drawn back for reloading, is attached to the rear end 4 of the bucket. 60

Below the plate 8 and removably secured to the bucket-end 4 by bolts 9, is a plow-attachment 10. This has a vertical sheet metal wall 11, the outer face of which is in the same plane with the outer face of the adjacent bucket-side 3. It also has a vertical sheet-metal wall 12 which extends obliquely from the corner of the bucket opposite wall 11 to the outer end of the wall 11, and the outer angle is braced by a fillet plate 13. 70 The oblique wall 12, is on that side of the plow which is toward the main mass of down coal to be gathered by the bucket, here shown as on the left hand side of the bucket. But when the coal to be gathered is on the right hand side of the bucket the left hand plow is removed by unbolting it and a plow with a side sloping in the opposite direction is substituted. 75

In either case, that is, whether the plow-attachment be right or left handed, its bottom is sloped upwardly from the rear end of the bucket, and the outer lower corner of the plow-bottom is rounded as shown in Fig. 1, to keep it from digging into the 80 floor of the mine. 85

In the operation of my invention, all of the coal in the path of an empty bucket drawn back rear-end first, to the place of beginning of the coal gathering operation, 90 is pushed out of the path of the bucket, in advance of the latter, and over to the main mass of down coal to be gathered and moved by the bucket. The way is kept clean and the breaking and grinding of lumps spilled 95 from the bucket in its forward travel is avoided. 100

Having thus fully described my invention what I claim as new and wish to secure by Letters Patent is—

1. The combination, with a coal gathering bucket, of a plow having an oblique side which extends from one side of the path of the bucket to the other. 105
2. The combination, with a coal gathering 110

bucket having a closed end, of a plow extending rearwardly of the end and having an oblique side.

3. The combination, with a coal gathering bucket having a closed end and a pair of sides at least one of which is substantially at right angles to the end, of a plow extending rearwardly of the end, and having an oblique member reaching from the plane of one bucket side to the plane of the other.

4. The combination, with a coal gathering bucket having parallel sides and a transverse end, of a plow extending rearwardly of the end and having an oblique member extending across the path of the bucket.

5. The combination, with a coal gathering bucket having parallel sides and a rear end at right angles to the sides, of a plow removably secured to the end and comprising a side the outer face of which is in the plane

of the outer face of one of the sides of the bucket and a plow side oblique to the first plow side and extending from the opposite corner of the bucket to the far end of the first plow side.

6. The combination, with a coal gathering bucket, of a plow having an oblique side which extends across the path of the bucket and having an upwardly and rearwardly sloping bottom.

7. The combination, with a coal gathering bucket, of a detachable plow having an oblique side extending across the path of the bucket and having an upwardly and rearwardly sloping bottom.

Signed at Petersburg, county of Pike, State of Indiana, this the 6th day of January, 1925.

NORMAN H. McCLEVEY.
